LESLIE A. COOPER, OF SPRINGFIELD, MASSACHUSETTS, ASSIGNOR OF ONE-HALF TO
GEORGE W. KIMBALL, OF SPRINGFIELD, MASSACHUSETTS.

SANITARY DRINKING-FOUNTAIN.

1,031,051.

Specification of Letters Patent.

Patented July 2, 1912.

Application filed August 3, 1911. Serial No. 642,070.

To all whom it may concern:

Be it known that I, LESLIE A. COOPER, a citizen of the United States of America, and resident of Springfield, in the county of Hampden and State of Massachusetts, have invented certain new and useful Improvements in Sanitary Drinking-Fountains, of which the following is a full, clear, and exact description.

- 10 This invention relates to improvements in sanitary drinking fountains of a kind in which a horizontal water pipe having at its free end an upstanding nozzle or delivery appliance is effective, under horizontal swinging movement of such pipe, to secure the opening of a valve which controls the flow of water from the supply so that the stream or jet will issue in a vertical or fountain like manner at the upstanding 15 nozzle to be drunk thereat,—such description of fountain also comprising a basin shaped member surrounding the drinking nozzle and with which a pipe is connected in an encircling and inclosing relation to 20 the water delivery pipe and which leads to 25 a waste conduit.

The object of the present invention is to provide a sanitary drinking fountain of the class above indicated which will be not only 30 entirely efficient and operative without derangement for an indefinite time, but which, moreover, by reason of the comparatively few parts comprised therein and the manner of their combination and coöperative arrangement, permits of the production of a 35 fountain of the greatest possible simplicity and cheapness.

The invention is described in conjunction with the accompanying drawings and is 40 defined in the claims.

In the drawings:—Figure 1 is a substantially central vertical section through the drinking fountain. Fig. 2 is a sectional view on a larger scale of important components of the device given for clearer illustration. Fig. 3 is a central sectional view of the water delivery appliance, at the drinking end of the fountain and comprising a volumetric governor or regulator. Fig. 4 45 is a plan view of Fig. 3.

In the drawings, A represents a stationary vertical water supply pipe which is open at its upper end and is surrounded by a vertical stationary water waste pipe B of con-

siderably larger diameter and the upper end of which is located somewhat below the upper end of the pipe A.

C represents a stationary annular body which in its specific construction as here shown comprises an axially vertical annular section a screw engaged with the upper portion of the waste pipe, another annular section above and in axial alinement with the first named section, internally screw threaded, and provided with an external outwardly extending flange c at its bottom and a flanged and internally threaded coupling ring d which unites said sections a and b and confines the packing ring e between their abutting ends.

D represents a head having an inclosed chamber f therein with which the upper end of the supply pipe communicates, and also having a passage g leading horizontally from the chamber f through a lateral extension or boss g². The said head D is made with a depending hub like portion h provided with external screw threads i and having engagement with the internal screw thread j in the upper portion or section of the aforementioned annular body so that when the chambered head D is rotatively moved in one direction, say for a half or quarter of a circle, the head will have a bodily rising movement to carry its valve E upwardly 70 open and away from its closing relation to the upper end of the water supply pipe A.

The hollow hub like part h of the head has the passage k leading vertically therethrough from its lower end, the same being continued in the lateral passage extension k² which is separated from the intake chamber f by the partition web or wall m which is made with a vertical opening therethrough in the axial line of the head, the wall of such hole being screw threaded of corresponding pitch to the threads i and j of the aforementioned screw engaging parts b and h, while the upper end portion of the water supply pipe is correspondingly 75 threaded for engagement through such hole in the partition.

Referring to the valve E and the manner of its inclusion in the chambered head,—such head has a screw threaded bore in 80 through its top in axial alinement with the supply pipe; and in a lower portion of his bore the externally threaded valve plug is

- adjustably engaged and downwardly protrudes into the chamber for coaction with the delivery end of the supply pipe. The lower end of the valve plug is provided with 5 a seating disk or packing o , and the valve plug has a screw driver slot in its upper end. Another screw plug q is engaged in the upper portion of the said threaded bore n to have a locking engagement against the top 10 of the valve plug, so that when the valve is properly adjusted and the plug q tightly set against it, there can be no shifting or displacement of the valve relatively to the rotative head D.
15. A water delivering pipe arm G is connected with the head as shown in Fig. 1 in such manner that the passage therethrough has communication with the horizontal passage g which leads from the chamber f in the 20 head; and another pipe H of comparatively large diameter surrounds the pipe G and connects with the lateral extension k^2 of the passage k which leads downwardly through the depending hub like portion of the head 25 D for free communication with the waste pipe. The pipes G and H having the passage r between them are both connected at their outer ends by a screw engagement with a fitting J having a vertical internal passage 30 s and an upwardly opening separated chamber or passage t .

At the upper end of the passage s a water delivery appliance K is provided. This comprises an upstanding water delivery nozzle u , and it has in the chambered body below the nozzle a volumetric governor v for regulating the flow of the water for delivery, fountain like, at the nozzle. This 35 governor comprises no part of my present application but it is illustrated as a desirable provision for the fountain. The delivery nozzle is surrounded by a basin L, the bottom of which opens into the chamber t in the fitting J with which the waste pipe arm 40 45 H has connection.

M represents the casing which surrounds, and is rotatively adjustable relatively to the upper portion of the aforesigned annular body C, the same here being shown as resting on a coupling ring d. This casing M has a boss or hub w internally thereof at its lower portion through which a set screw w^2 is inserted for binding the casing M when adjusted tightly to the annular body. Q represents a spiral spring for which said casing forms the closure, such spring encircling the upper section of the annular body C and has its ends respectively secured as indicated at x and x^2 to the 50 55 60 chambered head D and to the casing M. The casing serves in addition to a means for inclosing, protecting, and concealing the spring, also a means through the rotation thereof of regulating the tension of the spi-

pose of automatically turning the head after the fountain has been opened for its reversed rotation to insure the closing thereof.

The head D is made with a depending annular flange y at a proper location, and as 70 shown in Figs. 1 and 2 so that it covers and forms a guard for the upper open end of the spring case M.

The engagement of the depending hub like portion of the chambered head with the 75 upper portion of the stationary annular body is by screw threads of comparatively "quick" pitch so that by a comparatively small revoluble movement of the head and the parts carried in horizontal extension 80 thereof, the valve, which is as one with the head, will have ample opening movement upwardly away from the top of the water supply pipe A.

I claim:

1. In a sanitary drinking fountain, in combination, a vertical stationary water supply pipe open at its upper end, and a vertical stationary waste pipe loosely surrounding the supply pipe and having its upper end located below the upper end of the latter, a stationary annular member connected with and extending above the top of the waste pipe, a head having an inclosed chamber therein into which the upper open end 95 of the supply pipe communicates, also having a passage leading horizontally from said chamber, having a depending portion screw engaged with said stationary annular member, and also having a passage separated from the chamber in such head communicating with the waste pipe passage and also having a horizontal extension, the said chambered head having a valve member therein coacting with the delivery end of the supply pipe, 100 a comparatively small horizontal pipe connected with the horizontal passage of said head and provided with an upwardly extending water delivery appliance, another and larger horizontal pipe loosely surrounding the said smaller pipe, having its passage 110 in communication with the aforementioned horizontal passage-extension, and a basin shaped member surrounding the water delivery appliance and having communication 115 at its bottom with the said larger pipe.

2. In a sanitary drinking fountain, in combination, a vertical stationary water supply pipe open at its upper end, a stationary annular member surrounding the supply 120 pipe somewhat below its upper end, a head having an inclosed chamber therein with which the upper end of the supply pipe communicates, also having a passage leading horizontally from said chamber, said annular member having a screw threaded portion with which the screw threaded portion of the head engages, and said chambered head having a valve member therein coact- 125

1 a horizontal pipe connected with the horizontal passage of said head provided with an upwardly extending water delivery appliance, a casing surrounding and rotatively 5 adjustable relatively to said annular member having a spring therein in reaction between such casing and said head for imparting rotative return movement to the latter, and means for the confinement of said casing in its adjustment on the annular member.

3. In a sanitary drinking fountain, in combination, a stationary water supply pipe open at its upper end, and a vertical stationary waste pipe loosely surrounding the supply pipe having its upper end located below the upper end of the latter, a stationary annular body comprising an axially vertical annular section screw engaged with the 15 upper portion of the waste pipe, another annular section above and in axial alignment with the first named section, internally screw threaded and externally flanged at its lower portion, and a flanged coupling ring 20 uniting said sections, a head having an inclosed chamber therein with which the upper end of the supply pipe communicates, also having a passage leading horizontally from said chamber and provided with a depending hub like portion externally threaded and screw engaged within the upper section of the aforesaid annular body and having an annular passage therethrough, the vertical portion of which communicates with 25 the upper open end of the waste pipe while with its horizontal portion a pipe of comparatively large diameter is connected, a valve member fixed within the chambered head and coacting with the delivery end of the supply pipe, a basin 30 shaped member surrounding the water delivery appliance having communication at its bottom with the said comparatively large horizontal pipe, a casing surrounding and rotatively adjustable relatively to the upper 35 portion of said annular body, about the upper edge of which the aforesigned depending annular flange is disposed, and a spiral spring in said casing, surrounding the annular body having its ends respectively secured to the chambered head and to the casing, and a screw for detachably confining the casing in its rotative adjustment relatively to the annular body.

4. In a sanitary drinking fountain, in combination, a stationary water supply pipe

open at its upper end, and a vertical stationary waste pipe loosely surrounding the supply pipe having its upper end located below the upper end of the latter, a stationary annular body connected at its lower portion 55 to the upper end of the waste pipe, and having screw threads within its upper portion, a head having an inclosed chamber therein with which the upper end of the supply pipe communicates, also having a passage leading 60 horizontally from said chamber, provided with a depending hub like portion externally threaded and screw engaged within the upper portion of the annular body, having a passage therethrough comprising a vertical portion which communicates with the upper open pipe of the waste pipe and having a horizontal extension with which a horizontal pipe of comparatively large diameter is connected, the said head having a 65 depending annular flange widely encircling the upper portion of the depending hub like part of such head, a valve member fixed within the chambered head and coacting with the delivery end of the supply pipe, a 70 comparatively small horizontal pipe connected with the horizontal passage of the head which leads to the valve chamber therein and is provided with an upwardly extending water delivery appliance, a basin 75 shaped member surrounding the water delivery appliance having communication at its bottom with the said comparatively large horizontal pipe, a casing surrounding and rotatively adjustable relatively to the upper 80 portion of said annular body, about the upper edge of which the aforesigned depending annular flange is disposed, and a spiral spring in said casing, surrounding the annular body having its ends respectively secured to the chambered head and to the casing, and a screw for detachably confining the casing in its rotative adjustment relatively to the annular body.

Signed by me at Springfield, Mass., in 95 presence of two subscribing witnesses.
